CLAIM

The ornamental design for a adapter, as shown and described.

DESCRIPTION

FIG. 1 is a front, right and top perspective view of a adapter showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the adapter showing its data cable in the first bent state;

FIG. 10 is a perspective view of the adapter showing its data line in the second bent state;

FIG. 11 is a perspective view of the adapter showing the data line in the third bent state;

FIG. 12 is an enlarged partial view of FIG. 1; and,

FIG. 13 is an enlarged partial view of FIG. 7.

The Dash-Dash broken lines in the figures illustrate portions of the adapter that form no part of the claimed design. The Dash-Dot broken lines in FIGS. 1, 7 and 12-13 depict the boundaries of the enlargements that form no part of the claimed design.

The adapter is shown with a symbolic break in its length. The appearance of any portion of the article between the break lines forms no part of the claimed design.
